UNITED STATES PATENT OFFICE.

LEO STEINSCHNEIDER, OF BRÜNN, AUSTRIA.

PREHEATER FOR USE IN THE DISTILLATION OF PETROLEUM, TAR, AND THE LIKE.

1,302,988.

Specification of Letters Patent. Patented May 6, 1919.

Application filed September 17, 1918. Serial No. 790,363.

To all whom it may concern:

Be it known that I, LEO STEINSCHNEIDER, a subject of the Emperor of Austria, residing at Brünn, in Moravia, Austrian Empire, have invented certain new and useful Improvements in Preheaters for Use in the Distillation of Petroleum, Tar, and the like, of which the following is a specification.

In the petrol and tar industry pre-heaters for the crude oil or charge are used for the better utilization of the heat used in distilling. According to the present invention, the pre-heater is so constructed that the vapors or gases may take a vertical course, as it is found that a better dephlegmation occurs in this manner, the gases undergoing a gravitational stratification, as well as a separation by condensation.

The structure is also preferably so arranged that a natural circulation of the crude oil may take place in the pre-heater. Means are also preferably provided for controlling the circulation of the crude oil, and hence the condensation of the vapors or gases passing through the pre-heater. The vertical arrangement of the pre-heater and the natural circulation of the crude oil therein also contribute to a gravitational separation of the crude oil and the water contained therein.

The heat of either the vapors, or the distillate, or both, may be utilized in the pre-heater.

Several embodiments of the invention are illustrated in the accompanying drawing.

Figure 1 illustrates in vertical section a pre-heater according to the present invention.

Fig. 2 is a transverse section of the construction shown in Fig. 1.

Figs. 3 and 4 are views similar to Figs. 1 and 2 of a further embodiment of the invention.

Figs. 5, 5^a, 6 and 7 are vertical sectional views of further embodiments.

1 designates a vertical cylindrical tank or vessel provided with a cover and serving for receiving the fluid material (crude oil) to be heated. 2 designates the normal fluid level of the crude oil or the like in the pre-heater. 3 designates a dephlegmator which is arranged in the cylindrical tank 1. The dephlegmator may comprise a drum having the headers or ends 4, 4 and tubes 5 secured in the headers 4, as shown in Figs. 1-4, or a series of tubes 21 connected to manifolds 20

and 22, as shown in Figs. 5-7 inclusive. The vapors or gases coming from the still-head 6 pass through tube 7 into the dephlegmator 3, in or around the tubes, and, rising, pass out of the drum 3 through a pipe 8 to a condensing coil, and from there, after its condensation, to the receiving house. By the rising of the distillate vapors or gases, in the dephlegmator 3 a stratification results, according to the specific gravity of the vapors, and this stratification is assisted by the effect of the variously heated strata of crude oil, tar or the like, on the vapors passing vertically in the dephlegmator. The fluid (crude oil) to be pre-heated, Figs. 1-4, has passage through the tubes 5 and surrounds the sides of the dephlegmator 3, as well as the headers 4 thereof. The condensate in the dephlegmator 3 flows opposite to the distillate gases 75 and collects on the lower header 4, from which position it is carried off by pipes 9 and may thence advantageously pass through a coil 10, in order to cool down the condensate and pre-heat thereby the contents of 80 the pre-heater. The condensate may then pass to the receiving house through a pipe 11.

In order to obtain a good circulation of the fluid contents of the pre-heater, an open 85 jacket 12 is arranged around the dephlegmation apparatus. The jacket has one end at a height above the floor 13 of the pre-heater and has its other end a distance beneath the fluid level 2. The fluid which is warmed by 90 the dephlegmator 3 rises upward and continually draws after it the cooler fluid situated in the lower part of the pre-heater. The heated fluid in the vessel 1 may be conducted to the still through a pipe 25, the 95 fluid preferably being taken from the upper part of the jacket 12.

In the jacket 12, a valve 14 is situated, which can be so placed that it either leaves free the whole section of the jacket 12 or 100 only a part of same. 15 shows in dotted lines the position of the valve when partially open. By means of the valve 14 the operator can control the progress of the dephlegmation. When the valve 14 is in 105 closed position, flow of fluid through the jacket 12 and pre-heater is prevented. In this case the fluid located in the jacket 12 receives a higher temperature than that contained between the jacket 12 and the outer 110 walls of the pre-heater 1. The difference of temperature between the distillate gases in

the dephlegmator 3 and the fluid (crude oil) to which the heat is to be given, is diminished, and accordingly the condensation capacity of the dephlegmation apparatus is 5 lessened. When accordingly the fluid dephlegmator coming from pipe 9 contains too much of the light fluid constituents of the oil, the operator only needs to move the valve 14 to a partially open position, or 10 eventually, to a closed position, so as to reduce or stop the circulation of the crude oil in the pre-heater.

If this pre-heater is also to be used as a residue pre-heater, it is only necessary to arrange a coil 16 through which the residue enters from the still-head 6 by means of pipe 17 and leaves the pre-heater by pipe 18.

Figs. 3 and 4 show a pre-heater of similar construction to that shown in Figs. 1 and 2, 20 with the difference that in the casing of the dephlegmator 3, an intermediate wall 19 is arranged, so that the distillate gases coming from the pipe 7, rise on one side of this dividing wall, and fall on the other side. 25 The gases circulate around the tubes 5, and continue their course through pipe 8 exactly as in the previous embodiment. In the present instance two fluid dephlegmators are formed, which are separated by the dividing wall 19 and these pass through pipes 9 and 11 or 9' and 11' respectively to the receiving house.

Fig. 5 shows a further constructional form of the pre-heater. The vapors or gases from 35 the still-head, in this case, however, pass into the manifold 20 of the dephlegmator rising upward, inside the tubes 21 to manifold 22 and from there through tube 8 to the cooler into the receiving house. The dephlegmator 40 from the manifold 20 is again received by pipes 9.

By arranging a dividing wall 23 in the manifold 20 (Fig. 5^a) two fluid dephlegmators can be formed, which can then be 45 received by the pipes 9 and 9', the uncondensed distillate gases being led off through a pipe 8'.

Fig. 6 shows a further constructional form of pre-heater, in which both the manifold 20 and the manifold 22 are provided with a 50 dividing wall 23. The distillate gases rising upward from the compartment 20' of the manifold 20, pass through the first set of vertical tubes 21, into the compartment 22' 55 of manifold 22, thence into compartment 20'' of manifold 20 through a pipe 24. From compartment 20'' of manifold 20 the gases rise and leave the pre-heater through the pipe 8. In this case the fractions are discharged through pipes 9 and 9'.

It is clear that any number of such dephlegmation elements, as described in Figs. 1 to 6, can be arranged in a pre-heater, in which case each of the dephlegmation elements can either receive a separate jacket 12

for itself or all these elements may be provided with a common jacket. Such a form of construction is shown in Fig. 7 for a pre-heater of the horizontal construction where-in the gases not condensed in the first element pass to the second element and from there are directed to the third element and the fractionated fluids in the single elements are discharged through the pipes 26.

Also in vertical arrangements of pre-heaters the individual fractional elements can be arranged above each other so that for instance the first dephlegmator is formed in the upper elements, the second in the lower elements, etc., or the reverse.

I claim:

1. A pre-heater for use in the distillation of petroleum and the like products producing gases when heated, comprising a closed vessel containing the product to be distilled, a dephlegmator, the dephlegmator having an inlet and outlet for the distillate gases, vertical passages in contact with the contents of the vessel to conduct the distillate gases from the inlet to the outlet in a vertical direction, and an outlet or outlets for leading off the products condensed within the said dephlegmator, said dephlegmator and parts conducting the hot distillate gases being arranged inside the closed vessel, below the liquid level thereof, whereby said dephlegmator and parts conducting the hot gases do not come in contact with the gases which may collect in the space in the top of the closed vessel.

2. A pre-heater for use in the distillation of petroleum and the like products producing gases when heated, comprising a closed vessel containing the product to be distilled, a dephlegmator, the said dephlegmator comprising a system of vertical tubes in contact with the contents of the vessel, said dephlegmator also having an inlet, an outlet for the distillate gases and an outlet for the condensed products, said dephlegmator and parts conducting the hot distillate gases being arranged inside the closed vessel, below the liquid level thereof, whereby said dephlegmator and parts conducting the hot gases do not come in contact with the gases which may collect in the space in the top of the closed vessel.

3. A pre-heater for use in the distillation of petroleum and the like products producing gases when heated, comprising a closed vessel containing the product to be distilled, a dephlegmator, the said dephlegmator comprising a system of vertical tubes in contact with the contents of the vessel, and manifolds at the ends of the said tubes, said dephlegmator also having an inlet, an outlet for the distillate gases and an outlet for the condensed products, said dephlegmator and parts conducting the hot distillate gases being arranged inside the closed vessel, below

the liquid level thereof, whereby said dephlegmator and parts conducting the hot gases do not come in contact with the gases which may collect in the space in the top of the 5 closed vessel.

4. In a pre-heater for use in the distillation of petroleum and the like, the combination of a closed vessel adapted to contain the product to be distilled, a dephlegmator, said 10 dephlegmator comprising a plurality of sets of vertical tubes, the gases passing always upward along one surface of said tubes, a main pipe for conducting uncondensed gases from the top of one set of vertical tubes to 15 the bottom of another, and means adapting said dephlegmator to produce a plurality of fractions of the liquid condensed from said gases, the dephlegmator having an inlet and an outlet for the distilled gases, said dephlegmator and parts conducting the hot 20 distillate gases being arranged inside the closed vessel, below the liquid level thereof, whereby said dephlegmator and parts conducting the hot gases do not come in contact 25 with the gases which may collect in the space in the top of the closed vessel.
5. In a pre-heater for use in the distillation of petroleum and the like, the combination of a closed vessel adapted to contain the 30 product to be distilled, a dephlegmator, said dephlegmator comprising vertical tubes, a manifold at the base of said tubes, said manifold being in communication with the gas inlet and being divided, and an outlet for 35 the liquid condensed in each division of the manifold, said dephlegmator and parts conducting the hot distillate gases being arranged inside the closed vessel, below the liquid level thereof, whereby said dephlegmator and parts conducting the hot gases do 40 not come in contact with the gases which may collect in the space in the top of the closed vessel.
6. In a pre-heater for use in the distillation of petroleum and the like, the combination 45

of a closed vessel containing the product to be distilled, a dephlegmator comprising a system of vertical tubes arranged within said vessel and manifolds at each end of said tubes, partitions in said manifolds, a main communication tube connecting the space on one side of said partitions in one of the upper manifolds with a space in a lower manifold on the opposite side of the partition, whereby the distillate gases are caused to 50 pass always upward in the vertical tubes.

7. A pre-heater comprising a vessel containing the product to be distilled, a plurality of vertical tubes along one surface of which the distillate gases are led and thereby 55 caused to pre-heat the product to be distilled which is in contact with the other surface of said tubes, a jacket around said plurality of tubes and having an outlet for the contents of the vessel, and means for controlling the 60 circulation through said jacket.

8. A pre-heater comprising a vessel containing the product to be distilled, a vessel inside of said first vessel adapted to receive distillate gases, and a jacket between said 65 first and second vessels, said jacket having openings at its top and bottom and having the opening at its top below the liquid level in the first vessel.

9. A pre-heater comprising a vessel containing the product to be distilled, a vessel inside of said first vessel adapted to receive distillate gases, and a jacket between said first and second vessels, said jacket having 70 openings at its top and bottom and having the opening at its top below the liquid level in the first vessel, and means for controlling the circulation through said jacket.

In witness whereof I have hereunto signed my name in the presence of two subscribing 75 witnesses.

LEO STEINSCHNEIDER.
